Primary Examiner—Holly H. Bayham*Assistant Examiner*—Sheryl Friedman(74) *Attorney, Agent, or Firm*—Harness, Dickey & Pierce,
P.L.C.(57) **CLAIM**

The ornamental design for a wheel, as shown and described.

DESCRIPTION

FIG. 1 is an upper perspective view of the wheel, showing our new design;

FIG. 2 is another upper perspective view of the wheel;

FIG. 3 is a lower perspective view thereof;

FIG. 4 is another lower perspective view thereof;

FIG. 5 is a front view thereof;

FIG. 6 is a right elevation view thereof; and,

FIG. 7 is a left elevation view thereof; and,

FIG. 8 is a perspective view of the wheel shown in FIG. 1
being used with a wheeled shovel.

The details shown in broken lines are for illustrative purposes only and form no part of the claimed design.

1 Claim, 8 Drawing Sheets# US D555,565 S
